Primary Examiner — Lauren R Calve(74) *Attorney, Agent, or Firm* — JoAnn M. Seaton;
Griffiths & Seaton PLLC(57) **CLAIM**

The ornamental design for a hanger sock, as shown and described.

DESCRIPTION

FIG. 1 is a bottom, front perspective view of a hanger sock showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a top, front perspective view of the hanger sock of FIG. 1 shown during optional use.

The features shown in broken lines in FIG. 8 indicate optional environmental subject matter and form no part of the claimed design.

1 Claim, 4 Drawing Sheets(56)
